**INTERNAL SUSPENDED INSULATING CEILING
FOR STORAGE TANKS**

Stanley E. Sattelberg, Naperville, and Yuksel A. Selcukoglu, Chicago, Ill., assignors to Chicago Bridge & Iron Company, Oak Brook, Ill., a corporation of Illinois
Filed Dec. 15, 1965, Ser. No. 514,029
17 Claims. (Cl. 220—9)

This invention relates to insulated storage tanks where heat gain or loss is a problem. More particularly, this invention is concerned with improved tanks which have low heat-leak and heat-input characteristics and which are more economical to construct than many other tanks of comparable size and which are so constructed as to have a more trouble-free service life. The invention is especially suitable for refrigerated storage tanks, such as for storing liquefied gases.

Tanks are used to store various liquid and solid materials. Although many materials can be suitably stored at prevailing ambient temperatures, it is often advisable, and sometimes necessary, that products be stored in tanks at temperatures which differ significantly from existing ambient temperatures. Because of this, insulated storage tanks have been used to maintain solid or liquid products at lower and higher temperatures than ambient temperature, i.e., to keep heat in or out of the tank.

Insulated storage tanks are generally an enclosed metal shell having such insulation thereon as to reduce heat transfer to the extent considered practical. Such tanks can be used to store edible materials such as grains and oils where temperature control of the product is advantageous, as well as liquid petroleum products of all types.

A number of gases are stored in liquefied condition in insulated tanks. Among these gases are hydrogen, nitrogen, oxygen, methane (natural gas), ethylene and propane. One type of tank for storing such gases in liquefied form is comprised of an enclosed metal shell, usually of metal plate, which remains ductile at the extremely low temperatures at which the liquefied gas is stored.

The tanks store the liquefied gas at a temperature which maintains it liquid at about, or slightly above, atmospheric pressure. It is more economical to store liquefied gases at such pressures because of the increased cost of making large tanks or vessels strong enough to hold the liquefied gas at higher temperatures and pressures.

The tank shell comprises a flat metal bottom to which is secured a metal wall, usually cylindrical in shape, and joined to and supported by the wall is placed a metal roof usually dome-shaped, although it can be ellipsoidal, cone-shaped or some other shape. In such tanks, the bottom, wall and roof are insulated to reduce heat-leak sufficiently to obtain practical conditions of storage for a liquefied gas. The bottom and wall insulation generally presents no special problem of installation or maintenance because the bottom surface is flat and the wall cylindrical of large radius so panels or blocks of insulation can generally be applied easily. Insulating the roof, however, is a different problem because of its shape. Whether it is a spherical, ellipsoidal or conical dome, pre-assembled insulation panels or precast blocks cannot readily be fitted on the outside of the roof. In addition to the installation problem, all external roof insulation, which is the conventional way of insulating such tanks, is exposed to the weathering action of sun, rain, snow and ice and temperature extremes due to weather changes, as well as the mechanical forces and movements associated with weather and operating conditions. The roof insulation life is thus often short and maintenance high as compared to the more easily applied and better protected insulation on the vertical, cylindrical walls of the tank, and the insulated bottom which is inherently protected.

2

In order to overcome or avoid shortcomings involved with prior storage tanks, there is provided by this invention an improved, enclosed, insulated tank for storing solid and liquid materials at temperatures above and below ambient temperature, including liquefied gases, such as stored at about atmospheric pressure. The tank has an enclosed metal shell having a metal bottom, a metal wall and a metal roof, with both the bottom and wall being insulated adequately to suitably retard heat-leak or heat-input. The area surrounded by the wall is enclosed by a roof which for practicing this invention is advisably of noninsulating metal plate but which can, if desired, be insulated. The improved liquid storage tank has an insulated, advisably fixed-position ceiling suspended from the roof by suitable means. The periphery of the insulated suspended ceiling conforms at least approximately to the inside horizontal shape of the tank wall.

Although the ceiling can contact the inside wall surface, there is advisably clearance provided between them. Such clearance is useful when the tank contains a liquid product or liquefied gas product so that vapor transmission can be effected by means of such clearance from below the ceiling to the space above it and from the space above the ceiling to the space below it. Vapor transmission to and from the spaces above and below the ceiling alternatively can be effected by suitable ports provided in the suspended ceiling or by a ceiling which is not gas tight. Vapor transmission between such spaces prevents creation of a pressure differential between such spaces from heat-leak, heat-input or such as by flashing of a liquid cryogen into the tank during filling, or emptying, which could cause damaging forces on the ceiling.

In order further to illustrate and describe the invention, it will be discussed further in conjunction with the attached drawings in which:

FIGURE 1 is a vertical section through an enclosed insulated storage tank, having a suspended insulating ceiling according to one embodiment of this invention;

FIGURE 2 is a horizontal section, partially broken away, through the tank wall of FIG. 1 above the upper surface of the ceiling;

FIGURE 3 is an enlarged, vertical, sectional view taken at line 3—3 of FIG. 2, showing structural detail of the insulated suspended ceiling;

FIGURE 4 is a horizontal, sectional view taken at the line 4—4 in FIG. 3;

FIGURE 5 is a vertical, sectional view on the line 5—5 of FIG. 2 and shows the structure used for supporting the abutting ends of joists used in the ceiling assembly;

FIGURE 6 is a vertical, sectional view on the line 6—6 of FIG. 2 and shows cross-bridging used to stiffen the joists;

FIGURE 7 is a vertical, sectional view showing the rafter means used for distributing the load of the suspended ceiling of FIG. 1 over the roof area;

FIGURE 8 is a horizontal section, partially broken away, through a tank wall above the upper surface of another embodiment of the insulated ceiling; and

FIGURE 9 is a partial vertical section through an enclosed insulated storage tank and shows structural detail for the same insulated suspended ceiling embodiment shown in FIG. 8.

In the drawings, the same number is used to identify the same structural element wherever it appears.

With reference to FIG. 1, a supporting foundation 10, such as of concrete, is set into the earth as a foundation and on top of it is placed insulating material 11 of a suitable thickness and which is capable of bearing the combined load of the tank and its contents when filled. On top of insulation 11 is placed a metal bottom 12 to which tank wall 13 is secured at the bottom edge, such

as by welding. The wall 13 is advisably cylindrical. The external surface of wall 13 is provided with insulation 14 of sufficient thickness to retard heat-leak or heat-input enough to permit practical storage of a product in the tank. Enclosing tank wall 13 is roof 15 which is dome-shaped. A peripheral ring portion 16, of thicker metal plate than the upper portion 17 of the roof, is provided to strengthen the roof and stiffen the wall and support the ends of rafters 18 reinforcing the roof as shown in FIGS. 3, 5 and 7. Rafters 18 follow the internal contour of the roof. The rafters are advisably metal angles as in FIG. 7. Rafters 18 need not be used when the plates are made thick enough to carry the load without stiffening.

Connected to the bottom of the rafters 18, or directly to the roof plate, and running approximately normal to the radial rafters are load-distributing members 19, as shown in FIGS. 5 and 7, which more or less conform to the contour of the roof. Fastened at spaced apart locations on the load-distributing members 19 are plates 20 as shown in FIG. 5, from which elongated suspending members 21 hang vertically downward to support member 22 to which it is connected such as by welding. The members 22, as shown in FIG. 1, run parallel to each other throughout the width of the tank.

Between adjacent, parallel supporting members 22 is positioned a conventional open web bar joist 23, or other lightweight structural member which is supported at each end by adjacent members 22, except for the ends of the joist in proximity to the tank wall 13. The ends of the joists 23 adjacent the tank wall are supported by plate 24, as shown in FIG. 3, which is connected to member 25. The supporting elongated member 26, similar to members 21, is connected at its lower end to member 25 and at its upper end to plate 27 which is connected to the lower surface of the roof ring 16. The member 25 forms a ring which extends around the ceiling edge although the ceiling periphery extends slightly further to about the tank wall.

The open web bar joists 23 are composed of bar 28, as shown in FIG. 3, which is bent into a series of W shapes, and is affixed between top cord member 29, which is essentially U-shaped, and lower cord member 30, which is also U-shaped, as shown in FIG. 6. Joining upper cord 29 and lower cord 30 at the end of the joist is rod 31 as shown in FIG. 3. Member 32 is placed at the end of the joist and is connected at the lower side of the upper cord 29. The member 32 is essentially like the lower cord 30 in cross-section and provides a foot area for resting the end of the joist on bearing surface 24.

In order to stiffen the joists, which are arranged in parallel lines extending across the vessel, bridging, advisably of bar stock, can be run in parallel rows normal to the joists to connect the lower cords 30. Thus, in FIG. 6, bar 33 can be extended from one lower cord 30 to the lower cord of the next adjacent parallel joist. Furthermore, bar 34 can extend from the lower cord of a joist adjacent the tank wall 13 upwardly at an inclined angle to connect with member 25 as shown in FIG. 6. Member 25 forms a ring having a diameter slightly less than the diameter of the tank wall. Supporting the circular member 25 at such location, in a manner similar to membrane 26, is elongated member 36.

Covering the joist network is decking 37, advisably of the type which has channels running parallel to the side edges of the panels. The decking is shown in FIGS. 1 to 3 and 5. The decking 37 is placed normal to the joist and is of sufficient length to advisably span three or more joists. The decking has channeled areas 38 to provide rigidity and strength. The decking is advisably not run completely to the vessel wall. Expandable metal lath 39, as shown in FIG. 3, is formed to have a horizontal section and a vertical edge which is placed approximately in contact with the inside of the tank wall. The expandable metal lath 39 is secured to the top surface of the adjacent decking 37, such as by welding, and extends entirely

around the ceiling periphery. Instead of metal decking, decking of wood, plastic or other suitable materials can be used.

Any suitable insulation 39, which will reduce heat-leak or heat-input enough, can be placed on the upper surface of decking 37 in a thickness sufficient to give the desired results. The insulation may be preformed and blocks of suitable size positioned in place on the decking, or loose insulation of the granular or flocculent-type can be used. Furthermore, insulation of the foam-type, such as polyurethane foam, can be foamed in place directly on the decking to provide the desired insulation 39.

FIGS. 8 and 9 illustrate another embodiment of the invention. Tank wall 50 of metal is externally insulated 51. The tank roof 52 is constructed of metal rings 53 which overlap at 54. A heavier metal plate ring 55 runs around the periphery of the roof and rests on the top edge of wall 50. Metal plates 56 and 57 complete the roof shell, which is shown uninsulated.

A series of rafters 58, such as angle shapes, are axially connected to the underside of the roof to reinforce it. The rafters can be made in sections and joined by plates 59 to Z-ring girders 60 welded to the roof. Suspended from the girders 60 are rods 61. Similar rods 62 are suspended from the inner periphery of the roof and may be attached to the rafter ends as shown. Enough rods are employed to support the suspended ceiling. For a 100 foot diameter tank about fifty to sixty rods are employed in the outer two circular courses A and B, having radii of about 48 and 28 feet respectively, and about fifteen to twenty rods in circular course C, having a diameter of about 15 feet.

The suspended ceiling is composed of flat sheet metal decking 63 fabricated from sheets of appropriate size and shape. FIG. 8 gives a representative arrangement of sheets and shapes used in fabricating the flat ceiling. To support the flat ceiling sheet a compression ring 64 is placed near about the periphery of the sheet. Only one such compression ring is necessary to support the flat ceiling sheet. However, to provide further reinforcing and to restrict sag of the sheet, one or more additional circular supporting rings 65 are provided. The suspension rods 61 and 62 are joined to compression ring 64 and supporting rings 65 to suspend the ceiling in fixed position. Insulation 66 is placed on the metal sheet 63 to a depth adequate for the purpose. The space between compression ring 64 and tank wall 50 is advisably insulated 67 by a material which is flexible and somewhat porous to permit vapor transmission. A blanket of glass fibers can be used for this purpose and it can be supported by an outward projecting lip 68 of the flat metal sheet 63.

Although all the drawings show the insulated ceiling substantially planar and positioned horizontally in the tank, it is within the scope of the invention to suspend the insulated ceiling in a conical, domed or other configuration. There is usually, however, no advantage in such shaped suspended insulating ceiling and for most purposes a planar, horizontally suspended ceiling is satisfactory. Furthermore, the depth of the insulation layer on the decking or other means used to support the insulation by the suspension system can be of uniform thickness or the insulation thickness can be increased at selected ceiling areas if the heat-leak or heat-input is greater in such areas than others. Thus, under certain conditions it might prove advisable to increase the depth of the insulation around the periphery of the insulated ceiling since there could be more heat-leak or heat-input at the upper part of the tank wall than the central part of the suspended ceiling.

The suspended ceiling is advisably located below the junction of the upper edge of the insulated wall with the outer edge of the roof. The metal wall constitutes a direct path for heat to flow, such as from a warm metal roof to a refrigerated liquid in the tank below the insulated ceiling. The portion of the metal wall extending above the

insulated ceiling is insulated. This prevents heat transfer and also prevents sweat and frost when the tank is to store a refrigerated liquid. Heat flowing downward from the portion of the wall above the insulated ceiling, when the tank is used to store a cold product, is replaced by heat from the metal roof, heat from the stratifying warm gas above the suspended ceiling, and heat from the outside air by heat-leak through the wall insulation. The heat flowing into the refrigerated, stored liquid through the path provided by the extension of the metal wall to the warm roof, although expected to be large, unexpectedly is small and insignificant. For example, in a 126 foot diameter refrigerated ammonia tank with ambient temperature at 110° F., this heat flow is equivalent to the normal heat-leak through a ring of normally insulated wall (5 in. foam glass on outside of 0.25 in. wall) only 1.4 feet high extending around the circumference of the tank. The reduction in temperature of the metal wall to roof junction, due to the heat flow through the extended shell with an ambient temperature of 110° F., is only 15° F.

This combination of an insulated suspended ceiling and an uninsulated roof provides an unusually suitable combination for storage of materials, whether the product is to be kept below or above ambient temperature, because of the surprisingly low heat transfer through that portion of the tank wall above the insulated ceiling. Elimination of roof insulation, without sacrificing efficiency, lowers the cost and provides a tank which can be expected to have a longer life with far less trouble than when the roof is externally insulated.

By extending the metal wall above the insulated ceiling, a controlled temperature gradient is achieved between the roof, whether it be hotter or colder than the stored product, and the tank wall which is hot or cold according to the temperature of the stored product. This greatly increases the efficiency of the tank. Controlled heat-leak or heat-input renders the tank suitable for storage of hot or cold products at temperatures much higher or lower than ambient temperature.

Although the most suitable position of the ceiling below the tank wall roof juncture is readily calculated precisely, it is usually suitable to place the ceiling about 1 to 3 feet below the said juncture in a tank to be used for storing a refrigerated liquid. For storing other products, whether solid or liquid, where heat-input or heat-leak is not as important, the ceiling can be placed even closer to the roof.

An important feature of this invention is the suspension means, particularly for large tanks, which distributes the weight or load of the ceiling over a substantial and perhaps, major part of the roof. This may be achieved by means of the rafters and/or girders connected to the inside surface of the roof. Such structure prevents deformation of the roof which could otherwise likely result by simple attachment of the elongated suspending members directly to a point on the inside surface of the roof. The combination of rafters and load-distributing members spreads the load from the location of attachment of the elongated vertical members over most of the roof area.

It is also advisable that the suspended insulating ceiling be positioned in the tank to be above the full capacity level of the tank.

The provision of a suspended insulating ceiling in a tank for cryogenic storage permits the use of metals for the roof construction which are not adapted under other conditions for such purposes. The metal used for the roof need not be one which can withstand the refrigerated conditions to which the tank walls and bottom are subjected because the roof is at no time cooled to anywhere near the temperatures of the tank wall and bottom during service. The roof operates at substantially ambient, instead of refrigerated, temperature which allows the use of a less expensive roof material. This can result in sig-

nificant cost reduction since more economical materials can be used in the construction of the roof than would be the case if the roof had to be constructed to withstand the refrigerated conditions encountered by the tank bottom and wall during storage such as of a cryogenic liquid in the tank.

Various changes and modifications of the invention can be made and, to the extent that such variations incorporate the spirit of this invention, they are intended to be included within the scope of the appended claims.

What is claimed is:

1. An enclosed tank having a metal shell with a metal bottom, a metal wall and a metal roof, the bottom and wall each having a layer of insulation applied thereto and

15 the roof comprising a noninsulated metal plate supported upon the top edges of the wall, and an insulated fixed-position ceiling suspended by means attached to the inside of the roof, said ceiling conforming about its periphery to the internal horizontal configuration of the tank at the ceiling location and being suspended in the tank above the intended full capacity level of the tank.

2. A tank according to claim 1 in which the insulated ceiling is substantially planar and horizontally positioned in the tank with the ceiling periphery adjacent the wall

25 and the ceiling insulation is of about uniform thickness throughout its area.

3. An enclosed cylindrical tank having a metal shell with a metal bottom, a metal wall and a metal roof, the entire bottom and wall each having insulation applied to the outside thereof and the roof comprising a noninsulated metal plate supported upon the top edges of the wall, and an insulated fixed-position ceiling suspended by a plurality of spaced-apart elongated members attached to the inside of the roof and the ceiling, said ceiling conforming about its periphery to the internal horizontal configuration of the tank at the ceiling location and being suspended in the tank above the intended full capacity level of the tank.

4. A tank according to claim 3 in which the insulated ceiling is substantially planar and horizontally positioned in the tank in contact with the cylindrical wall and the ceiling insulation extends throughout its area.

5. A tank according to claim 3 in which the elongated members by which the ceiling is suspended are vertical and are attached to rafter means secured to the inside of the roof to distribute the ceiling load over a substantial area of the roof extending around the location of attachment of the elongated vertical members to the rafter means.

6. An enclosed cylindrical tank for storing a refrigerated liquid at a pressure slightly higher than atmospheric pressure, said tank having a metal shell with a metal bottom, a metal wall and a metal roof supported upon the top edges of the wall, the entire bottom and wall each having insulation applied thereto to reduce heat-leak adequately to efficiently store a refrigerated liquid in the tank, and an insulated fixed-position ceiling suspended by a plurality of spaced-apart elongated members attached to the inside of the roof and the ceiling, said ceiling conforming about its periphery to the internal horizontal configuration of the tank at the ceiling location and being suspended in the tank above the intended full capacity level of the tank.

7. A tank according to claim 6 in which the roof is noninsulated and the insulated wall extends above the level at which the ceiling edge meets the wall thereby providing a controlled temperature gradient between the roof and the tank wall to control heat-leak into the tank contents through the extended metal wall.

8. An enclosed cylindrical tank having a metal shell with a metal bottom, a metal wall and a metal roof, the bottom and wall each being insulated to retard heat transfer therethrough, the roof comprising a metal plate supported upon the top edges of the wall and at least insufficiently insulated to suitably store a refrigerated liquid

in the tank, and an insulated fixed-position ceiling suspended by a plurality of spaced-apart elongated members attached by load-distributing means to the inside of the roof and also attached to the ceiling, said load-distributing means comprising a plurality of rafters secured to the inside of the roof and following the roof contour, and a plurality of connecting beams which extend across and are connected to the rafters and to which the elongated members are connected at spaced-apart locations, said ceiling conforming about its periphery to the internal wall configuration of the tank at the ceiling location and being suspended in the tank above the intended full liquid level of the tank.

9. A tank according to claim 1 in which the ceiling comprises a plurality of parallel spaced-apart joists supported by the suspending means attached to the roof, bridging between the joists to stiffen them against movement, sheet decking secured to the top of the joists to complete an insulation supporting platform and insulation on the platform of a thickness adequate to retard heat-leak enough for practical storage of a refrigerated liquid in the tank.

10. An enclosed cylindrical tank for storing a refrigerated liquid at a pressure slightly higher than atmospheric pressure, said tank having a metal shell with a metal bottom, a metal wall and a domed metal roof, the entire bottom and wall each having sufficient insulation to reduce heat-leak enough to practically store a refrigerated liquid in the tank, the domed roof comprising a metal plate supported upon the top edges of the wall and insufficiently insulated if at all to suitably store a refrigerated liquid in the tank, and an insulated fixed-position ceiling suspended by a plurality of spaced-apart elongated members attached by load-distributing means to the inside of the roof and also attached to the ceiling, said load-distributing means comprising a plurality of radial rafters secured to the inside of the roof and following the roof contour, and a plurality of connecting beams which extend across and are connected to the rafters and to which the elongated members are connected at spaced-apart locations, the ceiling comprising a plurality of radially spaced-apart joists supported by the elongated suspending members, bridging between the joists to stiffen them against movement, sheet decking secured to the top of the joists to complete an insulation supporting platform and insulation on the platform of a thickness adequate to retard heat-leak enough for suitable storage of a refrigerated liquid in the tank, said ceiling conforming about its periphery to the internal wall circumference of the tank at the ceiling location and being suspended in the tank above the intended full liquid capacity level of the tank.

11. A tank according to claim 10 in which transmitting means are provided for flow of gas or vapor from below to above the ceiling, and from above the ceiling to below the ceiling.

12. A tank according to claim 10 for storage of a refrigerated liquid cryogen in which the roof is made of a metal normally unsuitable for refrigerated temperatures involved in cryogenic storage.

13. A tank according to claim 1 in which the insulated wall extends above the level at which the ceiling edge meets the wall thereby providing a controlled temperature gradient between the roof and the tank wall to control heat transfer to or from the tank contents.

14. An enclosed tank having a metal shell with a metal

bottom, a metal wall and a metal roof, the bottom and wall each having a layer of insulation applied thereto and the roof comprising a moninsulated metal plate supported upon the top edges of the wall, and an insulated fixed-position ceiling suspended from the inside of the roof and conforming about its periphery to the internal horizontal configuration of the tank at the ceiling location and being suspended in the tank above the intended full capacity level of the tank, said ceiling including a continuous layer of substantially flat sheet metal having a compression member joined thereto near about its periphery.

15. An enclosed tank for storing a refrigerated liquid, said tank having a metal shell with a metal bottom, a metal wall and a metal roof supported upon the top edges of the wall, the bottom and wall each having insulation applied thereto and an insulated fixed-position ceiling suspended from the inside of the roof and conforming about its periphery to the internal horizontal configuration of the tank at the ceiling location and being suspended in the tank above the intended full capacity level of the tank, said ceiling including a continuous layer of substantially flat sheet metal having a compression member joined thereto near about its periphery.

16. An enclosed tank for storing a cryogenic liquid, said tank having a metal shell with a metal bottom, a metal wall and a metal roof, the bottom and wall each having insulation applied thereto and the roof comprising a noninsulated metal plate supported upon the top edges of said wall, and an insulated fixed-position ceiling suspended from the inside of the roof and conforming about its periphery to the internal horizontal configuration of the tank at the ceiling location and being suspended in the tank above the intended full capacity level of the tank, said ceiling including a continuous layer of substantially flat sheet metal having a compression ring member joined thereto near the periphery of the ceiling, a second ring member joined to the sheet metal layer and positioned concentrically thereto and to the compression ring and inwardly from the compression ring to further support the sheet metal layer, and suspension means suspending the ceiling from the roof comprising tension members joined to the rings and to supporting means on the inside of the roof.

17. An enclosed tank for storing a cryogenic liquid, said tank having a metal shell with a metal bottom, a metal wall and a metal roof supported on the top edges of the wall, the bottom and wall each having a layer of insulation applied thereto and an insulated fixed-position ceiling suspended from the inside of the roof and conforming about its periphery to the internal horizontal configuration of the tank at the ceiling location and being suspended in the tank above the intended full capacity level of the tank.
